UNITED STATES PATENT OFFICE.

JERVIS R. HARBECK, OF DETROIT, MICHIGAN, ASSIGNOR TO DETROIT CAN COMPANY, OF DETROIT, MICHIGAN, A CORPORATION OF MICHIGAN.

METHOD OF MANUFACTURING PROOFED PAPER BODIES.

1,173,268.

Specification of Letters Patent.

Patented Feb. 29, 1916.

Application filed January 23, 1911. Serial No. 604,146.

To all whom it may concern:

Be it known that I, JERVIS R. HARBECK, a citizen of the United States, residing in Detroit, in the county of Wayne and State 5 of Michigan, have invented a new and useful Improvement in Methods of Manufacturing Proofed Paper Bodies, of which the following is a specification.

My invention relates to improvements in 10 the manufacture of waterproofed paper or fibrous bodies for cans.

Heretofore in the manufacture of convolute wound waterproofed can bodies, it has been customary to apply or introduce 15 the asphaltum or waterproofing compound in a heated and liquid condition between successive layers or coils of the convolute wound paper body, or else to introduce it in a dry and powdered form between successive 20 layers, and then subject the paper body to heat to fuse the asphaltum or water proofing compound. Both these methods are more or less objectionable, and slow, expensive, and uncertain in operation, and 25 both require a relatively large amount of asphaltum or proofing compound to be used, as it is applied directly to the porous and relatively coarse and thick paper or fibrous material of which the body or tube is made, 30 and both require special machines or appliances, the former being liable to gum up and interfere with the operation of the body making or tube winding machine and the latter requiring a special heating and 35 fusing step which may be more or less uncertain or defective in rendering the paper or fibrous body completely impervious to passage of liquids or gases.

The object of my invention is to provide 40 an improved method or process of manufacturing waterproofed or liquid and gas proofed paper or fibrous can bodies or tubes, by use of which the difficulties heretofore experienced may be overcome, the 45 waterproofed bodies or tubes manufactured very rapidly and cheaply and rendered thoroughly impervious to passage of liquids or gases, and with a relatively small amount of asphaltum or proofing material, 50 and without the necessity of special machines or appliances. The method or process I employ to practically accomplish this object or result, and this constitutes my invention, consists in introducing between the successive coils or layers of the paper or

other fibrous tube material of which the body or tube is formed, an extremely thin, dry, solid, flexible, continuous film of asphaltum or proofing compound supported and embraced between two layers of thin, 60 close paper which are firmly united thereto and secured together thereby, the thin paper exterior coating of the asphaltum or proofing film adapting it to be glued or adhesively united to the coils or layers of tube 65 material with which it contacts.

In practising my invention, the composite proofing layer or member of asphaltum film and thin paper is applied in the flat to the upper, adhesive-coated surface of the 70 paper of fibrous material web as said web is being wound into the convolute paper body. The composite proofing layer or member extends once around the paper body or tube and it may be applied at any of the 75 successive layers or coils of the tube. It is, however, preferably applied at one of the intermediate layers or coils instead of at the outer or inner ones.

In practice, the web of paper or tube-material, coated upon one side with adhesive, is wound around the mandrel for one or more layers, then the composite proofing layer is applied to the adhesive coated face of the paper web, the winding mandrel being 80 preferably stopped during this operation, and then the winding is continued, thus winding the composite adhesive layer around the body, and then the winding may be continued for one or more further layers, 85 if desired. In this way the paper bodies may be manufactured very rapidly and cheaply, and at the same time be thoroughly proofed against passage of liquids or gases therethrough. In this way it will be observed, however, that the composite proofing layer or member comprising the asphaltum or proofing film and the two layers of thin 90 close paper between which it is embraced and to which it is secured, is adhesively 95 united upon one side or face only to the web of tube material, and that the paper body or tube is thus formed with an unglued surface or line of cleavage between one face of the composite proofing layer and the adjacent face of the tube-paper web. But this 100 in practice I find to be no objection, as the finished paper body is substantially as rigid, stiff and strong as though all of its successive layers were glued or adhesively united 105 110

together. The composite proofing layer or member, is, as before stated, preferably composed of a flexible, dry, solid, continuous and extremely thin film of asphaltum or proofing compound, embraced between and firmly secured to two other thin layers of paper; but if desired, my invention may be practised by having the thin paper upon one face only of the film of asphaltum or proofing compound, in cases where it is not desired or required that both faces of the composite proofing layer or member be of a character adapted to be glued or adhesively united to an adjacent layer.

15 In the accompanying drawing forming a part of this specification, to enable my invention to be more fully understood and practised by those skilled in the art, I have shown at Figure 1 a side elevation of a paper body winding or tube machine suitable for use in practising my invention. Fig. 2 is a detail, vertical section showing the holder for the composite proofing layers or members. Fig. 3 is a perspective view illustrating a portion of the machine and showing one of the composite proofing layers or members applied to the upper adhesive material coated face of the web of tube material as it is being wound into a paper body or tube.

20 Fig. 4 is an enlarged detail cross section of a proofed paper body or tube as produced by my invention. Fig. 5 is a detail, perspective view of the composite proofing layer or member showing the film of asphaltum or proofing compound and the layers of thin, close paper, by which it is embraced, in part separated to better show its different parts. Fig. 6 is an enlarged detail cross section of the composite proofing

25 layer or member. Fig. 7 is a cross section of a modified form of the composite proofing layer or member in which the film of asphaltum or proofing compound is coated upon one side only with a layer of thin paper.

The convolute paper body winding or tube machine used in practising my invention may be of any suitable or well known construction. That which I prefer to employ, and which is indicated in Figs. 1 and 3 of the drawing, is substantially that shown and described in my Patent 862390 of Aug. 6, 1907, to which patent reference is made for a full showing and description of the tube machine.

50 In the drawing, 1 represents a roll of paper or other fibrous tube-material, the continuous web 2 of which passes over the coating roller 3 by which the glue, paste or adhesive material from the vessel 4 is applied to one face of the web. The web 2 of paper, after passing over the coating roller 3 which applies a coating of adhesive material to its under surface, then passes

55 around a tension roller 5 and roller 6 which

brings its adhesive coated face uppermost, and it thence passes over suitable guide rollers to the feed rollers 7, 8, which advance it to the winding mandrel 9, the end of the web being gripped to the winding 70 mandrel, preferably by suction in the usual manner. The winding mandrel 9 is preferably driven intermittently and winds the web of tube-material into a multiple lap tube or can body in two successive steps or 75 periods of winding.

The proofing layers or members 10, each comprising a dry, solid, continuous film of asphaltum or proofing compound 11 embraced between and secured to two thin 80 layers of paper 12, 13, one upon each face, are made long enough to extend once around the paper body, and the same are preferably contained in a movable magazine 14 which is raised and lowered at intervals as required to bring the lowermost proofing member 10 therein against the upper adhesive coated surface of the paper web 2, thereby sticking such lowermost proofing member to the paper web, so that, after the magazine is raised, it will feed forward with the web of tube-material and be wound around the mandrel between successive coils, layers or laminæ. The magazine containing the proofing members or layers 10 95 may be raised and lowered as required by any suitable means, preferably by a lever 15, which is operated by a cam 16 through the connecting link or push rod 17. After the winding is completed, the web of tube 100 material 2 is severed by the customary shears; and the feed rolls 7, 8 again advance the paper web 2 to the winding mandrel, and the operation is repeated. The thin paper 12, 13, to which the dry, solid, continuous film of asphaltum or proofing compound is united, serves to support the proofing film upon one or both sides, according as one or two layers of paper are employed, and also as a carrier to introduce 110 the proofing film at any point desired in the lamination of the paper body or tube 18.

If it is desired that the water proofing layer be near the inside of the completed body or tube, the proofing member 10 is 115 secured to the web or tube material at the earlier part of the winding operation. If the proofing layer is desired near the middle of the thickness of the paper body, it is applied to the web of tube material 120 near the middle of the portion required for each body, and if it is desired to be located near the outer portion of the thickness of the convolute wound paper body, the proofing member 10 is applied near the end of 125 the winding operation.

As illustrated in the drawing, the completed paper body or tube has a plurality of successive coils, layers or laminæ 19 inside the proofing member 10, and a plural- 130

ity of coils, layers or laminae 20 outside the proofing member or layer 10.

In the drawing, the relative thickness of the tube-material layers and proofing member layer is exaggerated for greater clearness of illustration, and this applies specially to the proofing film and the fibrous layers united thereto, all of which in practice are extremely thin.

10 I claim:—

1. The herein described process for making impervious paper container bodies, which consists in combining with thin porous paper a thin film of fused impervious cement to form a thin compound proofing sheet adapted to be glued or adhesively united to a layer of tube material, and providing a number of such proofing sheets 15 separate from each other; then intermittently winding a layer or sheet of tube material to form successive tubes, an adhesive being applied to a surface of the same; during said winding process intermittently applying said proofing sheets at separate intervals along the adhesive surface of the 20 unwound portion of said sheet of tube material.

25

material; and severing the sheet of tube material successively at the intervals between the separate proofing sheets.

2. The herein described process for making 30 impervious paper container bodies, which consists in applying between two layers of thin porous paper, a thin film of fused impervious cement to form a thin compound proofing sheet adapted to be glued or adhesively united to a layer of tube material, and providing a number of such proofing sheets 35 separate from each other; then intermittently winding a layer or sheet of tube material to form successive tubes, an adhesive being applied to a surface of the same; during said winding process intermittently applying said proofing sheets at 40 separate intervals along the adhesive surface of the unwound portion of said sheet of tube material; and severing the sheet of tube material successively at the intervals between the separate proofing sheets.

45 JERVIS R. HARBECK.
